UNITED STATES PATENT OFFICE.

CHARLES PHILIPPE BOUCHER AND FOUAUD JEAN CID, OF INDIANAPOLIS, INDIANA;
SAID BOUCHER ASSIGNOR TO ELECTRIC HEATER SUPPLY CO., OF WOONSOCKET,
RHODE ISLAND, AND SAID CID ASSIGNOR OF ONE-SIXTH TO M. ABRAHAM, OF
TORONTO, CANADA.

ELECTRIC WATER HEATER.

Application filed September 1, 1923, Serial No. 660,611, and in Canada October 20, 1923. Renewed August 27, 1925.

The present invention pertains to improvements in electric water heaters of that type in which a circulation takes place in the annular space between two concentric tubes.

5 The primary object of this invention resides in the provision of a device wherein the distance of flow through such space may be increased materially without increasing the length of the tubes. A number of tubes of 10 such concentric set are arranged in parallel and connected at their heads by headers divided into compartments in such a manner that the water is forced to flow through a plurality of said spaces before passing from 15 the inlet to the outlet of the device.

A further feature of the invention resides in a novel connection device between the electric switch and the water valve, whereby 20 current cannot flow to the heating coils unless water is admitted into the heating spaces.

The invention is fully disclosed in the following description and in the accompanying drawings in which:

25 Figure 1 is a vertical section corresponding to the line 1—1 of Figure 3;

Figure 2 is a section on the line 2—2 of Figure 1;

Figure 3 is a section on the line 3—3 of 30 Figure 1;

Figure 4 is an enlarged fragmentary longitudinal section of one of the units;

Figure 5 is a section on the line 5—5 of Figure 4;

35 Figure 6 is still further enlarged detail of a portion of Figure 4; and,

Figure 7 is a side elevation of the valve and switch device.

The device comprises an outer housing or 40 casing 1 of elongated construction and any suitable cross section. In the ends are fitted headers, the upper one 2 of which includes a cover 3, a bottom 4, and a peripheral wall 5. The lower header 2' is of similar construction, including a top 3', bottom 4', and side walls 5'. The bottom 4 of the header 2 and the top 3' of the header 2' are apertured as indicated by the numerals 6 and 6' respectively, and a plurality of outer tubes 50 7 are supported in these apertures by being secured in any desired manner to the interior wall thereof. The cover 3 of the header 2 and the bottom 4' of the header 2' are

likewise apertured as at 8 and 8' in alignment with the apertures 6 and 6', the latter 55 apertures being of greater diameter than those at the outer extremities of the header, for the purpose of supporting a plurality of inner tubes 9 which are disposed in concentric relation with the outer tubes 7. The 60 annular spaces 10 between the concentric tubes are relatively very small, being about .02 of an inch in width. The outer tubes 7 are each surrounded by a spirally wound ribbon 11 of nichrome, which is employed 65 as the resistance element. The remaining space within the casing 1 defined by the headers and the exterior walls of the outer tubes is filled with an insulating substance 12 which further serves to hold the resist- 70 ance ribbon in position. It will be observed from Figures 4, 5 and 6 that each spiral ribbon is separated from immediate contact with the tube which it surrounds by means of an insulating sleeve 13.

75 Within the inner tubes 9 are inserted porcelain or similar columns or cylinders 9', the same being previously wound with spirals of resistance ribbon 11'. The annular spaces thus formed with the inner tubes 80 are filled with a refractory substance 12' which is poured in the nature of a paste and allowed to harden.

By way of example, the embodiment illustrated in the drawings comprises five sets, 85 A, B, C, D, E of concentric tubes. The upper header is divided by means of the irregular partitions 14 and 15 into three compartments 16, 17 and 18. The compartments 17 and 18 enclose the tops of B—D and 90 C—E respectively, while the top of set A is confined within the compartment 16. The lower header is divided by means of irregular partitions 14' and 15' into compartments 16', 17' and 18' which are not individually 95 coextensive with the aligned compartments of the upper header. In contrast with Figure 2 or the upper header, it is to be noted that the lower ends of sets A and D are enclosed within the compartment 16', the sets 100 B and E are confined within the compartment 17', while the compartment 18' encloses the lower end of set C. The upper and lower ends of the casing 1 are provided respectively with inlet and outlet nipples 105 19 and 20 which communicate with the cor-

responding headers, the inlet nipple extending into the compartment 16 and the outlet nipple leading from the compartment 18'.

The operation of the device is as follows:

5 Current is supplied to the resistance ribbons, as is already well known in the art. The water entering the inlet nipple 19 flows into compartment 16 and downwardly through the annular space a of the set A, whereby
10 it reaches the compartment 16' in the lower header. The water being under pressure from compartment 16' is forced upwardly through the annular space d of set D, thus entering compartment 17 of the upper header. Since
15 this compartment also includes the upper end of set B, the water flows down the annular space b of the latter and into compartment 17' of the lower header. The flow continues in this manner up the annular
20 space e of set E and down the space c of set C into the compartment 18' of the lower header which compartment communicates with the outlet 20.

In Figure 7 is illustrated a novel device
25 in which the switch governing the current through the resistance ribbons is controlled by the water valve for the purpose of preventing a flow of current in the absence of a corresponding flow of water. Within the
30 casing 21 is disposed a three point switch of conventional construction which is controlled by the knob 22. This casing is located beneath the water valve 23, and the stem of the latter is bifurcated at its lower
35 end as at 24 for engaging the knob 22. In the conductor 25 leading from the three point switch are interposed a pair of contacts 26 normally spaced by means of the spring 27. A bag or bellows 28 is positioned on the
40 spring and is in fluid communication with the valve 23 through the piping 29. The switch and valve are so adjusted that the former is closed when the valve handle 30 is turned. Water then flows into the bellows
45 28 increasing the weight of the same whereby the circuit is closed through the contacts 26. In case the valve is defective or the main water valve is closed, the bellows 28 will not increase in weight, and consequently
50 the circuit will not be closed. In this way there can be no flow of current through the resistance ribbons in the absence of a flow of water.

While a specific embodiment of the invention has been illustrated and described, it is to be understood that various alterations in the details of construction may be made without departing from the spirit of the invention as indicated by the appended claims.

Having thus fully described the invention, what we claim as new and desire to protect by Letters Patent is:

1. A water heater comprising a plurality of units, each unit including an outer and

an inner tube spaced from one another, headers at the ends of said units and communicating with the spaces between the tubes of said units, a water inlet formed in one of said headers, a water outlet formed in the remaining header at a point diagonally opposite the water inlet, a partition in the first header forming a compartment including the water inlet and an end of one of said units, a partition in the remaining header forming a compartment including the opposite end of said unit, and the corresponding end of an additional unit, a second partition in said last named header forming a compartment including the corresponding end of still another of said units and the water outlet, a second partition in the first named header including the opposite end of said last named unit and the corresponding end of still another unit, whereby water can pass from the inlet to the outlet only through all the spaces of said units.

2. A water heater comprising a plurality of units, each unit including an outer and an inner tube spaced from one another, headers at the ends of said units and communicating with the spaces between the tubes of said units, a water inlet formed in one of said headers, a water outlet formed in the remaining header at a point diagonally opposite the water inlet, a partition in the first header forming a compartment including the water inlet and an end of one of said units, a partition in the remaining header forming a compartment including the opposite end of said unit, and the corresponding end of an additional unit, a second partition in said last named header forming a compartment including the corresponding end of still another of said units and the water outlet, a second partition in the first named header including the opposite end of said last named unit and the corresponding end of still another unit, the partitions in each header being spaced to form additional compartments which contain the corresponding ends of the remaining units, whereby water can pass from the inlet to the outlet only through all the spaces of said units.

3. An electric water heater comprising a plurality of units, each unit including an outer and an inner tube spaced from one another, a refractory column inserted within and spaced from said inner tube, resistance ribbon wound around the column and spaced from the inner tube, refractory material filling said tube, headers at the ends of said units and communicating with the spaces between the tubes, and partitions dividing said headers into non-coextensive compartments.

In witness whereof we have hereunto set our hands.

CHARLES PHILIPPE BOUCHER.
FOUAD JEAN CID.
